CLUTCH PURSE

Richard W. Samuelian, Fresno, Calif.

Application February 28, 1955, Serial No. 34,757

Term of patent 3½ years

(Cl. D87—3)

FIG. 1.

FIG. 2.

FIG. 3.

Fig. 1 is a top plan view of a clutch purse showing my new design.

Fig. 2 is a side elevation thereof, the side opposite being identical to that shown.

Fig. 3 is an end elevation thereof, the opposite end being of the same appearance as that shown.

I claim:

The ornamental design for a clutch purse, as shown.
